CIRCUIT INTERRUPTING DEVICE
Olav Freland, Milwaukee, Wis., assignor to McGraw-
Edison Company, Milwaukee, Wis., a corporation of
Delaware

Filed June 3, 1960, Ser. No. 33,755
11 Claims. (Cl. 200—146)

This invention relates to circuit interrupting devices and, more particularly, to load break disconnecting switches.

Load break disconnect switches generally comprise a disconnect switch having a circuit interrupter in parallel with its main disconnect contacts and which is adapted to interrupt the circuit after the switch has been opened. Providing a parallel circuit around the main disconnect contacts while they are opening, eliminates the tendency for an arc to be struck between the stationary contact jaw and the movable switch blade, should the switch be opened under load. The circuit interrupter usually comprises fixed and movable contacts disposed in arc extinguishing structure and means for separating said contacts after the disconnect switch has been opened.

It is an object of the invention to provide a load break disconnect switch which cannot be accidentally or inadvertently opened without moving its operating lever from one extreme position to another.

It is another object of the invention to provide a load break disconnect switch wherein the circuit interrupter cannot be reclosed until after the main switch contacts are closed so that said circuit interrupter is not required to carry heavy inrush currents.

A further object is to provide a load break disconnect switch with means for preventing the reopening of the disconnect contacts until after the circuit interrupter has been reset.

These and other objects and advantages of the invention will become more apparent from the detailed description of the invention taken with the accompanying drawings in which:

FIG. 1 is a side elevational view, partly in section, of the load break disconnect switch according to the instant invention, in its closed position;

FIG. 2 is a top plan view of the load break disconnect switch shown in FIG. 1, with parts broken away;

FIG. 3 is a front elevational view of the device with parts broken away;

FIG. 4 is a rear elevational view of the preferred embodiment of the invention, with parts broken away;

FIG. 5 is a view taken along lines 5—5 of FIG. 2;

FIG. 6 is a side elevational view of the device with its main contacts and interrupting contacts open; and

FIG. 7 shows a partial side elevational view of the preferred embodiment of the invention and illustrates the operation of its safety latch mechanism.

Referring to the drawings in greater detail, the invention comprises, in general, the combination of an air disconnect switch designated generally by the reference numeral 10 and a load interrupting device 11. The disconnect switch 10 includes switch blade means which comprises a pair of parallel switch blades 12 pivotally mounted on a pair of conductive frame members 14 which in turn are mounted atop a first porcelain bushing 16. A stationary contact jaw 18 is disposed atop a second porcelain bushing 20 and is engageable by the switch blades 12 when the latter are moved into their closed position.

As seen in FIGS. 2 and 3, one end of each of the switch blades 12 is received between a pair of vertical spaced apart, arms 24 on its associated frame member 14 and each is pivotally mounted therebetween by a hinge pin 26 which is received in suitably aligned openings in

2

the arms 24 and the switch blade 12. Bearing pressure is provided between arms 24 and switch blades 12 by spring washers 28 which surround each hinge pin 26 and which are forced against the surface of the outer arm 24 by nuts 30 received on the threaded outer end of each hinge pin 26. In this manner, good electrical contact is achieved between switch blades 12 and support arms 24 so that current interchange may be accomplished with a minimum of heating.

Each of the frame members 14 is mounted on a conductive base plate 32 which may be connected to one of the incoming or outgoing line conductors (not shown). The stationary contact jaw 18 comprises pairs of parallel contact fingers 34 affixed at their lower ends to a conductive base plate 36 which is adapted to be connected to the other line conductor (not shown).

15 The circuit interrupter 11 is located between switch blades 12 and includes a tubular housing 40 having stationary contacts 41 disposed near its contact jaw end and a movable contact rod 42 coaxially disposed for longitudinal movement relative to said stationary contacts. The outer shell of the tubular housing 40 is composed of any suitable insulating material such as Bakelite and its inner surface is composed of an arc quenching gas evolving material 43, such as fiber. A conductive end cap 45 is secured to one end of tube 40 and carries the stationary contacts 41 and on its inner surface and a by-pass rod 47 coaxially affixed to its outer surface. The other end of tubular housing 40 threadably receives a metallic guide bushing 48 having an axial bore 49 for slidably receiving the movable contact 42.

20 Integral with the upper surface of guide bushing 48 is an inverted U-shaped mounting bracket 50 whose arms 51 are each rigidly secured to one of the switch blades 12. In this manner, the switch blades 12 and the circuit interrupter 11 are rigidly affixed for unitary pivotal movement as said switch blades are rotated between their 25 opened and closed positions.

25 In addition, an elongate channel member 52 is affixed to the mounting bracket 50 and extends rearwardly therefrom. A longitudinal slot 53 is formed on each side of channel member 52 and each extends from the guide bushing 48 to a point slightly beyond pivotal axis of switch blades 12.

30 Referring specifically now to FIG. 2, it can be seen that the end of the movable contact rod 42 threadedly engages a guide block 54 which has a recess 56 for receiving a coaxially disposed contact opening spring 58 that extends between an eye 59 in the end of movable contact rod 42 and a cross pin 60 extending between the opposite sides of channel member 52 near its hinge end. As seen in FIGS. 2 and 5, guide block 54 is mounted for sliding movement between the sides of channel member 52 by a pair of integral guide shoulders 62 which extend longitudinally along the lateral sides of block 54 and which are disposed in slots 53. In a similar manner, an operating block 64, as shown in FIGS. 2 and 3, is also slidably mounted in slots 53 between guide block 54 and the hinge end of member 52 by guide shoulders 65 formed integrally on each lateral side thereof.

35 Disposed between each of the members 14 and the sides of channel member 52 is one of the vertical arms 68 of a U-shaped frame member 69. A second pair of parallel guide slots 70 are formed in the enlarged upper ends of arms 68 and in a parallel relation to slots 53 and each extends from a point adjacent the operating block 64 to the pivotal axis of switch blades 12. Extending laterally from each shoulder 65 of operating block 64, through slots 53 and into slots 70 are a pair of transverse operating pins 72.

40 The movable contact 42 of circuit interrupter 11 is held in its closed position shown in FIGS. 1 and 2 by a latch

link 73 which is engageable with a latch 74 formed on a lower edge of operating block 54. Latch link 73 is pivotally mounted on a shaft 75 journalled between a pair of ears 76 depending from each of the lateral sides of channel 52. A torsion spring 77, which surrounds shaft 75, urges rotation of latch link 73 in a counterclockwise direction. This rotation is limited by a transverse pin 78 extending laterally from latch arm 73 for engagement with one of the lower edges of channel member 52.

An inverted, U-shaped, operating handle 84 having a pull ring 85 and a pair of depending legs 86 which are pivotally mounted at their lower ends on a transverse shaft 88 extending between a bracket member 89 affixed to each of the switch blades 12. An operating link 90 is connected at one end to each of the depending legs 86 of operating handle 84 and at its other end to one of the transverse operating pins 72 projecting from operating block 64.

From the description thus far, it will be appreciated that when the assembly is in its closed position shown in FIGS. 1 and 2, rotation of switch blades 12 would tend to move operating block 64 in an arc whose center of curvature is located at the pivotal axis of said switch blades. Movement of operating block 64 in this manner, however, is prevented because of the engagement of operating pins 72 and stationary slots 70. Thus, when operating handle 84 is in its unrotated position, shown in FIGS. 1 and 2, switch blades 12 are locked in position because operating pins 72 prevent relative rotation between slots 53 in channel member 52 and stationary slots 70.

In order to release switch blades 12 for pivotal movement to their open position, operating handle 84 is rotated in a counterclockwise direction by a hook stick or the like, moving operating block 64 through the agency of operating rods 90 from its position in FIG. 1 to the left end of slots 70, as shown in FIG. 3. This places operating pins 72 at the rotational axis of switch blades 12. Further rotation of operating handle 84 is prevented by a pair of stop members 94 extending inwardly from each of the switch blades 12 and lying in the path of its pivotal movement. It can be seen that when operating pins 72 are coaxial with the rotational axis of switch blades 12 slot 53, carried by member 52, will be free to rotate relative to fixed slot 70 so that switch blade 12 can move out of engagement with contact fingers 34. In this manner, switch 10 is locked in a closed position until operating handle 84 has been fully rotated thereby minimizing the probability of accidental opening.

It will be recalled that when the switch is in its closed position, as shown in FIG. 1, latch arm 73 engages latch 74 to hold movable contact rod 42 in closed position. As the circuit interrupter 11 and the switch blades 12 begin to rotate in a counterclockwise direction from their closed positions, spring 77 holds pin 78 against the lower edges of channel member 52 as it rotates, so that latching members 73 and 74 will remain in engagement and movable contact 42 will remain latched. Current will, therefore, continue to flow through the load interrupter along a path defined by conductive base plate 36, stationary bypass contacts 104, fixed and movable contacts 41 and 42, the current interchange spring 45, guide block 48, the mounting bracket 50 and the switch blades 12. As a result, when the main disconnect switch is opened no arc will be struck between stationary contact fingers 34 and switch blades 12. After the switch blade 12 has cleared the stationary contact jaw 18, further rotation of the switch blades 12 will bring a trip pin 96 extending transversely from a depending leg 98 integral with latch arm 73 into engagement with the hooked end 100 of a trip lever 101 pivotally mounted between the legs 68 of frame member 69 and urged for rotation in a counterclockwise direction by torsion spring 102. This prevents further rotational movement of latch arm 73, so that as guide block 54 continues rotating with interrupter 11, latch 74 will

move out of engagement with the now stationary latch arm 73 whereupon guide block 54 and contact rod 42 are free to move to the left as viewed in FIGS. 1, 2 and 6 under the influence of opening spring 58, whereby the circuit is interrupted.

After the circuit interrupter has opened, continued rotation of the assembly will move by-pass rod 47 out of engagement with the stationary by-pass contacts 104. It will be appreciated that when the switch 10 is in this open position slots 53 and 70 will be out of parallelism so that operating pins 72 cannot be moved out of alignment with the pivotal axis of switch blades 12. For this reason, the operating handle 85 cannot be rotated in a clockwise direction to move the contact rod 42 into its closed position when the switch blades 12 are out of engagement with contact jaw 18. This prevents damaging inrush currents from flowing through interrupter 11 upon the reclosing of switch 10.

A safety latch assembly 110, shown in FIGS. 1, 4, 6 and 7, is provided to prevent the reopening of the disconnect switch 10 after switch blades 12 have been rotated from their opened to their closed position prior to the reclosure of circuit interrupter 11. This assembly includes a latch member 112 pivotally mounted by means of a pin 113 extending between a pair of vertical frame members 115 and biased for rotation in a clockwise direction by a torsion spring 120. Rotational movement of safety latch 112 is limited by a transverse pin 121 extending laterally from one side into an arcuate slot 123 formed in one of the frame portions 114. When switch blades 12 are in their closed position, as shown in FIG. 1, safety latch 112 is restrained with pin 121 near the upper end of slot 123 by a latch arm 124 affixed to a shaft 125 pivotally mounted between a pair of bracket members 126 secured to the base 36. In addition, a trip arm 127 is also rigidly attached to shaft 125. A torsion spring 129 biases shaft 125 in a counterclockwise direction so that trip arm 127 and latch arm 124 are urged toward their positions shown in FIG. 1.

Upon rotation of switch blades 12 and circuit interrupter 11 from their position shown in FIG. 1, shaft 88 will engage the upper end of trip arm 127 to rotate shaft 125 in a clockwise direction in opposition to torsion spring 129. This swings the end of latch arm 124 downwardly, thereby allowing safety latch 112 to rotate in a clockwise direction under the influence of spring 120, from its position shown in FIG. 1 until pin 121 engages the lower end of slot 123 as shown in FIGS. 6 and 7. When the switch 10 is thereafter reclosed, shaft 88 will move downwardly from its position shown in FIG. 6 to its position shown in FIG. 7 where it will be engaged by safety latch 130. This prevents switch blade 12 from being rotated out of engagement with stationary contact fingers 34. However, when operating handle 84 is rotated in a clockwise direction from its position shown in FIG. 7 to the position shown in FIG. 1, a cocking bar 132 extending between legs 86, is moved into engagement with safety latch 112 to rotate it in a counterclockwise direction until latch member 112 re-engages latch arm 124. It can be seen, too, however, that such rotation of operating handle 84 moves operating block 64 and guide block 54 to the right through the agency of operating links 90 until latch 74 re-engages latch arm 73 whereupon the circuit interrupter is again latched in closed position.

The safety latch assembly 110 is then reset so that the switch 10 may again be opened in the manner described above.

From the foregoing it can be seen that slots 53 and 70 and operating block 64 cooperate to prevent the accidental opening of switch 11 prior to the rotation of operating handle 84 from one extreme position to another. These members also cooperate to prevent the reclosure of circuit interrupter 11 prior to the reclosure of switch blades 12. In addition, safety latch mechanism 110 pre-

vents the opening of switch blades 10 when circuit interrupter 11 is open.

While only a single embodiment of the instant invention has been shown and described, other modifications will be apparent to those skilled in the art once the inventive concept is known. Accordingly, it is intended to cover in the appended claims all such modifications and variations which fall with the spirit of the invention.

I claim:

1. The combination of a load interrupting device and a disconnect switch, said disconnect switch including stationary contact means and switch blade means rotatable into and out of engagement therewith, an operating handle rotatably mounted relative to said switch blade between first and second positions, locking means connected to said switch blade and to said operating handle for preventing the rotation of said switch blade means to its open position until said operating handle has been rotated from its first to its second position, latch means for holding said circuit interrupter closed, means for tripping said latch means to open said circuit interrupter after said disconnect switch has been opened, said locking means also preventing the rotation of said operating handle from its second position to its first position after said switch blade means has been opened until the reclosure thereof, movement of said operating handle from said second to said first position after a reclosure of said disconnect switch being operative to relatch said circuit interrupter in closed position, and safety latch means for preventing the reopening of said disconnect switch after a reclosure thereof until said circuit interrupter has been latched closed.

2. A disconnect switch including stationary contact means and switch blade means pivotable into and out of engagement therewith, an operating handle pivotably mounted relative to said switch blade between first and second positions, locking means operatively associated with said switch blade and said operating handle for preventing the rotation of said switch blade means to its open position until said operating handle has been pivoted from its first to its second position, said locking means also preventing the rotation of said operating handle from its second position to its first position after said switch blade means has been opened until the reclosure thereof.

3. A disconnect switch having a pair of spaced apart terminals, switch blade means pivotally mounted on one of said terminals for engagement with the other, an operating handle movable relative to said switch blade means between first and second positions, a locking member slidably engaging said switch blade means and said one terminal for movement between an initial and a final position, said locking member being operative when in its initial position to prevent pivotal movement of said switch blade and inoperative to prevent such movement when in its final position, said operating member being connected to said operating handle for movement from its initial to its final position when said operating handle is moved from its first to its second position.

4. A disconnect switch having a pair of spaced apart terminals, switch blade means pivotally mounted on one of said terminals for engagement with the other, an operating handle movable relative to said switch blade means between first and second positions, a locking member slidably engaging said switch blade means and said one terminal for movement to the pivotal axis of said switch blade from a point remote therefrom so that said switch blade is free for pivotal movement to its open position, said locking member being operative in all other positions to prevent such pivotal movement, said locking member being connected to said operating handle for movement to said pivotal axis when said operating handle is moved from its first to its second position.

5. A disconnect switch having a pair of spaced apart terminals, switch blade means pivotally mounted on one of said terminals for engagement with the other, said

switch blade means having a first guide means formed therein, said one terminal having a second guide means formed therein and disposed adjacent said first guide means when said switch blade means is in its closed position, an operating handle pivotally mounted relative to said switch blade means between first and second positions, a locking member cooperatively engaging each of said guide means and movable therein between initial and final positions, said locking means being operative to prevent pivotal movement of said switch blade when in its initial position and inoperative to prevent such movement when in its final position, said operating member being connected to said operating handle for movement from its initial to its final position when said operating handle is moved from its first to its second position.

6. A disconnect switch having a pair of spaced apart terminals, switch blade means pivotally mounted on one of said terminals for engagement with the other, said switch blade means having a first longitudinal guide means formed therein, said one terminal having a second guide means formed therein adjacent said first guide means, said guide means being substantially parallel when said switch blade means is in its closed position, an operating handle pivotally mounted on said switch blade means between first and second positions, a locking member mounted on said switch blade means and cooperatively engaging each of said guide means for movement therein between an initial and a final position, said locking member being operative to prevent pivotal movement of said switch blade when in its initial position and inoperative to prevent such movement when in its final position, said operating member being connected to said operating handle for movement in said guide means from its initial to its final position when said operating handle is moved from its first to its second position.

7. A disconnect switch having a pair of spaced apart terminals, switch blade means pivotally mounted on one of said terminals for engagement with the other, said switch blade means having a first longitudinal slot formed therein and intersecting its pivotal axis, said one terminal having a second stationary slot formed therein and intersecting the pivotal axis of said switch blade means, said slots being substantially parallel when said switch blade means is in its closed position, an operating handle pivotally mounted relative to said switch blade means between first and second positions, a locking member mounted on said switch blade means and engaging each of said slots, said locking member being connected to said operating handle for movement in said slots to the pivotal axis of said switch blade means from a point remote therefrom when said operating handle is moved from its first to its second position.

8. The combination of a load interrupting device and a disconnect switch, said disconnect switch including stationary contact means and switch blade means rotatable into and out of engagement therewith, actuating means for rotating said switch blade means between its opened and closed positions, latch means for holding said circuit interrupter closed, means for tripping said latch means to open said circuit interrupter after said disconnect switch has opened, said actuating means being operative to relatch said circuit interrupter after said disconnect switch has been reclosed, and safety latch means for preventing the reopening of said disconnect switch after a reclosure thereof until said circuit interrupter has been latched closed.

9. The combination of a load interrupting device and a disconnect switch, said disconnect switch including spaced terminals and switch blade means pivotably mounted on one terminal for engagement with the other, operating means mounted for movement relative to said switch blade means, said circuit interrupter having separable contacts and latch means for holding said contacts in closed position, means for tripping said latch means to open said circuit interrupter after said disconnect switch

has opened, said operating means being connected to said interrupter contacts and movable between first and second positions to reclose the same after said disconnect switch has been closed, and safety means operable to latch said switch blade means in closed position upon the re-engagement thereof with said other terminal, said operating means also being operable to unlatch said safety means upon movement between its first and second positions, whereby said disconnect switch cannot be opened after its reclosure until said circuit interrupter has been latched closed.

10. The combination of a load interrupting device and a disconnect switch, said disconnect switch including spaced terminals and switch blade means pivotably mounted on one terminal for engagement with the other, operating means pivotably mounted on said switch blade for movement relative thereto between first and second positions, said circuit interrupter having fixed and movable interrupting contacts and latch means for holding said movable contact in closed position, means for tripping said latch means to release said movable contact after said disconnect switch has been opened, said operating means being connected to said movable contact and operable upon movement from its first to its second position to reclose said contacts after said disconnect switch has been reclosed, and a safety latch pivotably mounted on said other terminal and engageable with said switch blade means to hold the same in closed position upon the re-engagement thereof with said other terminal, said operating means being engageable with said safety means to rotate it out of latching engagement with said

switch blade means upon movement between its first and second positions, whereby said disconnect switch means cannot be opened after a reclosure thereof until said circuit interrupter has been latched closed.

11. The combination of a load interrupting device and a disconnect switch, said disconnect switch including stationary contact means and switch blade means pivotable into and out of engagement therewith, an operating handle rotatably mounted relative to said switch blade means between first and second positions, locking means connected to said switch blade means and to said operating handle for preventing pivotal movement of said switch blade means to its open position until said operating handle has been rotated from its first to its second position, latch means for holding said circuit interrupter closed, means for tripping said latch means to open said circuit interrupter after said disconnect switch has been opened, said locking means also preventing the rotation of said operating handle from its second position to its first position after said switch blade means has been opened and until the reclosure thereof, movement of said operating handle from said second position to said first position after a reclosure of said disconnect switch being operative to relatch said circuit interrupter in its closed position.
